UNITED STATES PATENT OFFICE.

JOHN BUNN BROWER, OF PHILADELPHIA, PENNSYLVANIA, ASSIGNOR OF
ONE-HALF TO ALBERT E. POTTS, OF SAME PLACE.

DESIGN FOR A SAFETY-PIN FRAME.

SPECIFICATION forming part of Design No. 22,948, dated December 5, 1893.

Application filed February 8, 1893. Serial No. 461,523. Term of patent 7 years.

To all whom it may concern:

Be it known that I, JOHN BUNN BROWER, a citizen of the United States, residing at Philadelphia, in the county of Philadelphia and State of Pennsylvania, have invented a new and original Design for Safety-Pins, of which the following is a specification.

The invention relates to a new and original design for safety-pins.

The object of the present invention is to provide an ornamental and attractive safety-pin; and the essential features reside in a pin having a loop with parallel sides and sigmoidal ends.

In the drawing, the figure is a plan view of a safety-pin showing my original design.

Referring to the drawing, 1 designates a wire loop having parallel sides 2 and 3 and provided with sigmoidal ends 4 and 5. The sigmoidal ends 4 and 5 are provided with similar opposite inwardly extending bends forming a narrow separating opening and divid-

ing the loop into two portions. The inward bends of the sides 4 and 5 form an H-shaped opening within the frame; and the opening 25 has similar side portions and a central connecting portion.

What I claim is—

The design for a safety-pin frame herein shown and described, the same comprising a 30 frame composed of straight parallel sides 2 and 3, and sigmoidal ends 4 and 5 connecting the ends 2 and 3 and having inwardly extending bends forming an H-shaped opening within the frame with side portions and a portion 35 6, as set forth.

In testimony that I claim the foregoing as my own I have hereto affixed my signature in the presence of two witnesses.

JOHN BUNN BROWER.
